IMPULSE STIMULATING APPARATUS

James A. Fizzell and James G. Golseth, Chicago,
Ill., assignors, by mesne assignments, to Re-
search Corporation, New York, N. Y., a corpora-
tion of New York

Application June 20, 1946, Serial No. 678,150

9 Claims. (Cl. 128—2.1)

1

This invention relates to an impulse stimulating apparatus and more particularly to an electrical impulse stimulating apparatus for the electrodiagnosis of peripheral nerve injuries.

Peripheral nerve injuries may be diagnosed by electrically stimulating muscle through the skin and observing the character of the muscle reaction in response to the stimulation. Diagnosis of the character of peripheral nerve injuries; i. e., to determine whether a nerve is divided or contused, by clinical examination not utilizing electrical stimulation, is often difficult if not impossible. While contused nerves usually recover spontaneously, those that are divided require operative repair and the sooner this is done the better are the results obtained. Therefore, the use of an electrical impulse stimulating apparatus is of great aid in diagnosing peripheral nerve injuries.

As the character of the muscle reaction to the electrical impulse stimulation furnishes a guide as to the type of nerve injury involved and because this muscle reaction will usually be controlled by the amount and duration of electrical current used as a stimulus, it is necessary to have an apparatus that will deliver the proper type of electrical current to the patient in precise controllable amounts. The operator must know definitely what the apparatus is delivering so that any variations in results can be attributed to the patient's condition and not to improper performance of the apparatus. Only then can these variations be properly interpreted in the light of established standards and only then can comparisons be made of results obtained by using different machines. Therefore, the apparatus must be a precise one and particularly this so if satisfactory results are to be obtained in clinical research of peripheral nerve injuries.

Our apparatus meets these standards. It will deliver monophasic (direct) current, which has been found to be preferable to multiphasic (alternating) current for electrodiagnosis of peripheral nerve injuries, in precise controllable amounts. The electric current is delivered in pulses controllable in duration and controllable in time interval between pulses so that, if desired, a practically continuous current can be obtained. The pulses are "square wave" pulses so that, when the electrical current is applied to the patient, it is applied practically instantaneously at full pulse amplitude value.

We also provide switching means for reversing polarity of the electric current delivered to the patient, since current polarity is a factor in elec-

2

trodiagnosis of peripheral nerve injuries, and for isolating the patient from the electric current when the value of current delivered to the patient is being measured, thereby avoiding patient discomfort.

In order that the character of the load; i. e., intermittent electric current application to the patient and variations in the electrical resistance of different patients, will not adversely affect the source of direct current, which may possess poor voltage regulation and hence affect the character of the electric current delivered to the patient, we provide means for obtaining a substantially constant electric current drain on the source of direct current during operation of our apparatus.

We are aware that apparatus has been proposed for use in electrodiagnosis which produces pulses of direct current and which includes an arrangement intended to effect a constant electric current drain on the source of direct current while the apparatus is in operation. However, we have found this prior art apparatus to lack sufficient precision for satisfactory usage in electrodiagnosis of peripheral nerve injuries by percutaneous stimulation. There is insufficient control of pulse duration and pulse frequency and the pulses obtained with this prior art apparatus are not "square waves." The result is that the overall precision of the prior art apparatus is not suitable for accurate electrodiagnosis and, in particular, is not suitable for comparing examinations made with different machines or for clinical research. We overcome the defects of this prior art apparatus by a novel combination of elements described hereafter.

Accordingly, an object of the present invention is to provide a new and improved apparatus for electrodiagnosis having means for generating pulses of direct current, means for delivering these pulses to a patient, and means for maintaining a substantially constant current drain on the source of direct current during operation of the apparatus.

Other objects of the present invention are to provide such an apparatus, wherein "square wave" pulses of direct current are produced with delicate control of the pulse current strength, the pulse duration and the interval between pulses, wherein the polarity of the current delivered to the patient can be reversed and, when the current is being measured, the patient can be isolated from the electrical circuit, and wherein the apparatus is portable and easy to set up and operate.

These and other objects of our invention will become apparent from the following detailed description taken in conjunction with the accompanying drawings, in which

Fig. 1 is a diagram of the electrical circuit of our apparatus with the polarity control switch shown in neutral position;

Fig. 2 is a diagram of the polarity switch position for making the exploring electrode the anode;

Fig. 3 is a diagram of the polarity switch position for making the exploring electrode the cathode, and

Fig. 4 is a frontal view of the apparatus housing, with the cover removed, showing the control panel and the members contained thereon and also showing the electrodes through which current is delivered to a patient.

Referring to Fig. 1, which illustrates an embodiment of our invention, the major parts of our invention include an output circuit designated at 10 and including electrodes 13 and 14 for delivering current to a load 15, such as a patient, a milliammeter 16 for measuring the intensity of the current delivered to the load, a pentode tube 17 for controlling the flow of current delivered to the load, and a switch assembly 18 for interconnecting the electrodes 13 and 14, the milliammeter 16 and the pentode 17, across the source of direct current; a compensating circuit 11 for maintaining a substantially constant current drain on the source of direct current and including a pentode 19, a voltage divider 20 and connections 21 and 22 interconnecting control elements of pentodes 17 and 19 with voltage divider 20 in a manner such that the total current drawn by the output circuit 10 and the compensating circuit 11 remains substantially constant during operation of our apparatus; and a multi-vibrator circuit 12 for generating pulses of direct current to be delivered to the load 15.

The electrodes 13 and 14 are of a type which can be conveniently applied to portions of the human body being examined and are illustrated in greater detail in Fig. 4. Electrode 13 is preferably made in ball form so that it can be pressed against the skin and the electrode is extended into an insulated handle portion 23 so that the electrode can be grasped by an operator and manipulated at will. This electrode is the "exploring" electrode and, in practice, is moved over the surface of the skin to determine the correct point for application of electric current. Electrode 14 is shown as constituting a substantially flat plate which can be clamped against a portion of the body and held stationary during application of electric current to the patient. Elastic clamping members can be used to clamp the electrode 14 to the patient and extensions 24 serve as guides for preventing slippage of the electrode 14 from the elastic retaining means. Electrode 13 is connected through lead 25 to stationary contacts 26 and 27 of switch assembly 18. Electrode 14 is connected through lead 28 to stationary contacts 29 and 30 of switch assembly 18.

Direct current is delivered to the electrodes 13 and 14 from the positive side 31 of the D. C. source. The current passes through milliammeter 16 before reaching the electrodes. After passing through the electrodes, the current passes through pentode 17 to the negative side 32 of the D. C. source. The milliammeter 16 is connected to the positive side 31 of the D. C. source by lead 33 and is connected to a movable contact mem-

ber 34 of switch assembly 18 by lead 35. The plate 36 of pentode 17 is connected to movable contact 37 and stationary contact 38 of switch assembly 18 by lead 39. Lead 21 connects the screen grid 40 of pentode 17 to the voltage divider 20 at point 41 and lead 42 connects the control grid 43 of pentode 17 to the output circuit 44 of multi-vibrator circuit 12 at points 45 and 46. Cathode 47 of pentode 17 is connected 10 through resistance 48 to the negative side 32 of the D. C. source.

In the compensating circuit 11 the plate 49 is connected to the positive side 31 of the D. C. source through lead 50. The screen grid 51 of pentode 19 is connected to a resistance 52, which is across the D. C. source, by lead 53, as is shown in Fig. 1. The control grid 54 of pentode 19 is connected to the voltage divider 20 at point 55 by lead 22. Cathode 56 of pentode 19 is connected, through resistance 48, to the negative side 32 of the D. C. source.

Multi-vibrator circuit 12 includes pentodes 57 and 58, capacitors 59 and 60, and resistances 61, 62, 63 and 64 connected in conventional electron-coupled multi-vibrator fashion, as is illustrated in Fig. 1, to produce "square wave" pulses of direct current. In the connection shown in Fig. 1, the screen grids 65 and 66 of pentodes 57 and 58, are used as plates for the performance of the switching function. A portion of the electron stream in pentode 58 reaches the plate proper 67 because this plate is made positive by its connection through resistance 68 to the positive side 31 of the D. C. source and this portion of the electron stream furnishes the voltage pulse in resistor 68 which is transmitted through lead 69, to the output circuit 44 of the multi-vibrator circuit 12. Thus the load is coupled to the oscillatory circuit through the electron stream in the tubes themselves. As will be evident to those skilled in the art, this manner of coupling achieves "square wave" pulses in the output and prevents changes in the load from affecting the frequency of oscillation. Resistances 63 and 64 are adjustable for changing the time constants of the circuits of the respective tubes 57 and 58. Control of the interval between pulses is obtained by adjusting resistance 63 and control of the duration of the pulses is obtained by adjusting resistance 64. Control of the pulse amplitude or current strength of the output pulses is obtained by adjustable resistance 70.

For portability, the electrical elements are housed in a casing 71 of size and shape as illustrated in Fig. 4. This casing is provided with a grip member 72 for carrying the casing and has a hinged cover, shown as removed, which covers the control panel 73. Mounted on the control panel are adjustable dials 74, 75 and 76. Dial 74 adjusts resistance 63 and thus controls the interval between pulses, dial 75 adjusts resistance 64 and thus controls the duration of the pulses, and dial 76 adjusts resistance 70 and thus controls the pulse current strength. Milliammeter 16 is mounted on control panel 73 and a switch handle 77 is also contained thereon for controlling the switch assembly 18. Leads 25 and 28 project from the control panel 73 through opening 78.

Switch assembly 18 is a three-position switch, which is illustrated as being in the middle, or neutral position in Fig. 1. The arrows 79 indicate that the movable contacts can be moved either to the left or to the right and these positions are indicated in Figs. 2 and 3 respectively. When the

movable contacts are in the position shown in Fig. 1, electrodes 13 and 14 are eliminated from the output circuit. When the movable contacts are in the position shown in Fig. 2, electrode 13, the exploring electrode, is the positive electrode, or anode, and when the movable contacts are in the position shown in Fig. 3, electrode 13 is the negative electrode. Thus, the direction of current passing through load 15 can be reversed by moving the movable contacts of switch assembly 18 to either extreme position. Movement of these contacts to the left, middle, or right hand positions can be effected by moving switch handle 77 to the left, middle, or right hand position.

The operation of our apparatus is as follows: When the switch 80 is closed, positive direct current flows to the output circuit 10, the compensating circuit 11, and the multi-vibrator circuit 12. In the switch position illustrated in Fig. 1, this current flows through milliammeter 16, through lead 35, through switch contacts 34 and 81, through connecting lead 82, through switch contacts 83 and 38, and through lead 39 to the plate 36 of pentode 17. Conduction of current through the pentode 17 to the negative side 32 of the D. C. source is controlled by control grid 43 which, in turn, is connected through lead 42 to the output circuit 44 of multi-vibrator circuit 12. It is a well known characteristic of electron discharge units such as, for example, the pentode 17, that operation of such a unit on the flat portion of its characteristic curve, that is, the curve illustrating the relationship between plate-voltage and plate-current, eliminates the variations in current caused by varying resistances. Pentode 17 is operated on the saturated portion of its plate voltage-plate current characteristic curve with the result that changes in plate circuit resistance, as will occur when load 15 is connected into the circuit, have little effect on the value of plate current. Pentode 17 is also biased so that when control grid 43 is driven in a positive direction by the action of multi-vibrator circuit 12 the pentode will conduct current to the negative side 32 of the D. C. source. Thus, it will be seen that for the switch position illustrated in Fig. 1, electrodes 13 and 14, and hence the load 15, are eliminated from the current path so that current readings can be taken without discomfort to the patient. Furthermore, resistance 84 is included in the multi-vibrator circuit 12 and this resistance, acting in conjunction with resistance 64, increases the time constant of resistance 64 and condenser 10 (which time constant controls the duration of the pulses applied to the subject), to such a value that a practically continuous current is passed by pentode 17 thereby enabling the operator to read milliammeter 16 without having the milliammeter needle fluctuating.

While current has been passing through the output circuit 10, additional current has also been passing through voltage divider 20 and pentode 19. When pentode 17 is non-conducting, voltage divider 20 and pentode 19 draw a substantially constant current. However, when pentode 17 is conducting, the screen grid 40 of pentode 17 draws current from voltage divider 20 through lead 21 with the result that the potential of point 55 on voltage divider 20 is reduced. Since control grid 54 of pentode 19 is connected by lead 22 to point 55, the control grid 54 is simultaneously made more negative, thereby reducing the current passed by pentode 19. Thus, as pentode 17 conducts, pentode 19 conducts a lesser amount of current and the circuit constants are chosen so

that the total current drain remains substantially constant whether pentode 17 is conducting or non-conducting.

When the switch contacts are in the position shown in Fig. 2, current passes from the positive side 31 of the D. C. source, through milliammeter 16, through lead 35, through switch contacts 34 and 26, through lead 25 to electrode 13, through the load 15, to electrode 14, from electrode 14 through lead 28, from lead 28 through switch contacts 30 and 37 to lead 39 and from there to plate 36 of pentode 17, whence pentode 17 conducts the current then passing through that tube to the negative side 32 of the D. C. source. Thus, in this switch position electrode 13 is the positive electrode. The compensating action of the compensating circuit 11 and the control effected by multi-vibrator circuit 12 are the same as was explained for the switch connection illustrated in Fig. 1, with the following exception.

When the movable switch contacts are moved either to left or right position, resistance 84 is shorted out by the action of movable contact 85 and stationary contacts 86 and 87. This restores control of the pulse duration to adjustable resistance 64, which can be varied as desired to achieve different pulse durations.

When the movable switch contacts are in the position illustrated in Fig. 3, current flows from the positive side 31 of the D. C. source, through milliammeter 16, through lead 35, through switch contacts 34 and 81, through lead 82, through switch contacts 83 and 29, through lead 28 to electrode 14, through the load 15 to electrode 13, from electrode 13 through lead 25 to switch contact 27, through switch contact 27 and switch contact 37 to lead 39 and from lead 39 to the plate 36 of pentode 17. Current then passes through pentode 17 to the negative side 32 of the D. C. source. Thus, in this switch position the electrode 14 is the positive electrode and electrode 13 is the negative electrode, or cathode. Operation of the compensating circuit 11 and the multi-vibrator circuit 12 is the same as was explained for the switch position illustrated in Fig. 1, and the resistance 84 is likewise shorted out by the action of switch contacts 85 and 87 to restore control of the pulse duration to the adjustable resistance 64.

Thus, the operator may apply direct current pulses of controllable duration and interval therebetween and of controllable strength to a load, such as a patient, and he can vary the polarity of the current passing through the load at will. The exploring electrode 13, which he will normally hold in his hand, can be made either an anode or cathode; i. e., a positive or negative electrode. When he desires to read the value of current that was delivered to the patient he merely has to throw the switch to neutral position and the patient is isolated from the circuit. Furthermore, the pulse duration is automatically thrown to practically continuous current so that he can read current value as a steady value and this value will be the same as the value of current delivered to the patient because the electronic tube controlling this current delivery is substantially unaffected by variations in its plate resistance. The power supply is unaffected by current drain because the current drawn by the output circuit is compensated by an additional circuit so that a substantially constant current drain is maintained on the current source.

It will be seen that we have provided a portable impulse stimulating apparatus of sufficient pre-

cision for use in accurate electrodiagnosis of peripheral nerve injuries preferably by percutaneous stimulation of muscle.

While we have referred to the use of our impulse stimulating apparatus for electrodiagnosis, it is to be realized that such an apparatus is susceptible to other uses. For example, it will find other electromedical uses, such as for electrotherapy and, in particular, the stimulating of paralyzed muscles resulting from peripheral nerve injuries and other neurological disorders. In short, such an apparatus can be used whenever it is desired to apply electrical current to a load, such as a patient, in the manner heretofore described.

Likewise, while we have described a particular embodiment of our invention, it is to be understood that we do not wish to be restricted thereto and that we intend to cover all modifications thereof which would be apparent to one skilled in the art and which come within the spirit and scope of our invention, as set forth in the appended claims.

We claim:

1. An apparatus for delivering pulses of direct current to a load and for maintaining a substantially constant current drain on the source of direct current while the apparatus is in operation comprising an output circuit having a pair of electrodes adapted to be connected to the load, a current intensity indicating device and a space discharge device, all adapted to be connected in series across the direct current source by a switch having three positions, in two positions of which the electrodes are in the output circuit but have different polarities and in the third position of which the electrodes are out of the output circuit and the current intensity indicating device and the space discharge device are connected in series across the direct current source, a compensating circuit having a second space discharge device connected, through a resistance, across the direct current source, said second space discharge device being biased to draw normally a constant current, and a connection between the first named space discharge device and the second space discharge device for lowering the current drawn by the second space discharge device, when the first named space discharge device is conducting, in an amount sufficient to keep the total current drain on the source of direct current substantially constant, a multi-vibrator circuit for generating pulses of direct current, said multi-vibrator circuit having means to vary the pulse duration, the interval between pulses and the pulse current strength, and a connection between the output circuit of said multi-vibrator circuit and a control member of the first named space discharge device whereby the current delivered to the load is controlled by the action of the multi-vibrator circuit.

2. An impulse stimulating apparatus for electromedical use or the like comprising an output circuit having a pair of electrodes adapted to be connected to a load, a current intensity indicating device, and a multi-element space discharge device, all adapted to be connected in series across a source of direct current by a multiple position switch having positions for reversing the direction of current to the load and for isolating the load from the output circuit, means for maintaining a substantially constant current drain on the direct current source during operation of the apparatus, an electron-coupled multi-vibrator for generating substantially square wave

pulses of direct current, said multi-vibrator including means for varying the pulse duration, interval between pulses and pulse current strength and a connection between the output circuit of said multi-vibrator and a control member of said multi-element space discharge device whereby operation of said space discharge device is controlled by said multi-vibrator.

3. An apparatus for electromedical use or the like comprising a source of direct current, an output circuit having a load circuit, a milliammeter and a space discharge device, all adapted to be connected in series across the direct current source by a multiple position switch, a compensating circuit having a second space discharge device connected, through a resistance, across the direct current source, said second space discharge device being biased to draw normally a substantially constant current, and means to decrease the current drawn by said second space discharge device when said first named space discharge device conducts by an amount sufficient to maintain the current drain on the direct current source substantially constant during operation of the apparatus, a multi-vibrator connected across the direct current source and means for impressing the output of said multi-vibrator on a control element of said first named space discharge device, said first named space discharge device being biased to respond to impulses produced by said multi-vibrator.

4. An apparatus for electromedical use or the like comprising a source of direct current, means for producing pulses of direct current, means for delivering said pulses to a load, said last named means including a pentode tube, a second pentode tube connected, through a resistance, across the direct current source, said second named pentode being biased to draw normally a substantially constant current, a voltage divider connected across the direct current source, a connection between a control element of said first named pentode and said voltage divider, a connection between a control element of said second named pentode and said voltage divider, said last named connection being at a less positive potential point on said voltage divider than said first named connection, whereby when current passes from the said first named pentode through a portion of said voltage divider and produces a voltage drop across said portion, the potential of said second named connection, and hence the potential of the control member of the second named pentode, is further decreased to decrease the current drawn by the second named pentode.

5. An apparatus for electromedical use or the like comprising a source of direct current, an output circuit having a pair of electrodes adapted to be connected to a patient, a milliammeter, and a pentode, all adapted to be connected in series across the direct current source by a three position switch having two positions for reversing the polarity of current delivered to the patient and a third position for isolating the patient from the output circuit while the milliammeter is being read, a compensating circuit having a second pentode connected, through a resistance, across the direct current source, a voltage divider connected across said source, and means interconnecting said voltage divider with both of said pentodes to maintain the current drain on the direct current source substantially constant during operation of the apparatus, an electron-coupled multi-vibrator connected across the direct current source for producing pulses of

direct current, said multi-vibrator including means for varying the duration of said pulses, the interval between said pulses and the amplitude of said pulses as desired, and a connection between the output circuit of said multi-vibrator and the control grid of said first named pentode, whereby variations in the potential of said multi-vibrator output circuit are impressed upon said control grid, said first named pentode being biased to be responsive to said potential variations.

6. An impulse stimulating apparatus for electromedical use or the like, comprising an output circuit having electrodes adapted to be connected to a load, a current intensity indicating device, and a multi-element space discharge device, all adapted to be connected in series across a source of direct current by a multiple position switch having at least one position in which the load is isolated from the output circuit, a multi-vibrator for generating pulses of direct current, said multi-vibrator including a resistance for controlling pulse duration and also including an output circuit, a connection between said output circuit and a control member of said multi-element space discharge device, said control element being biased to be operatively responsive to the output of said multi-vibrator circuit to control current flow through said multi-element space discharge device, and a shunt circuit through said multiple position switch for shunting out the resistance in said multi-vibrator when the load is isolated from the first named output circuit, whereby a practically continuous current is produced by said multi-vibrator and is impressed on said multi-element space discharge device control member to cause a practically continuous current to pass through the current intensity indicating device to facilitate reading the value of current.

7. An apparatus for delivering pulses of unidirectional current to a load comprising a source of unidirectional current, a first space discharge device, a multi-vibrator, a compensating circuit including a second space discharge device connected through a resistance across the electric current source, said second space discharge device being biased to draw normally a substantially constant current, means to decrease the current drained by said second space discharge device when the first space discharge device conducts by an amount sufficient to maintain the current drain on the said electric current source substantially constant during operation of the apparatus, means for impressing the output of said multi-vibrator on the control element of said first space discharge device, means for reversing the polarity of the pulse current delivered to the load, means to measure the intensity of the current being delivered to the load, and means to isolate the load from the

pulse-delivering means while the value of the current delivered to the load is measured.

8. An apparatus for delivering pulses of unidirectional current to a load comprising a source of unidirectional current, means including a multi-vibrator for producing pulses of unidirectional current, means including a space discharge device operatively responsive to the said first means, means for delivering pulses to the load, means to measure the intensity of the current being delivered to the load, means to isolate the load from the pulse-delivering means while the value of the current delivered to the load is measured, and variable resistance means connecting said last-named means to the pulse-producing means to cause said pulse-producing means to produce long briefly interrupted pulses while the current is being measured.

9. An apparatus for delivering pulses of unidirectional current to a load comprising a source of electrical potential, means connected across said source for setting up pulses of unidirectional current, a first thermionic valve connected across said source in series with the load, means for feeding said pulses to a control element of said valve, a second thermionic valve also connected across said source and normally biased to draw a given amount of current when the first valve is non-conducting, and circuit means interconnecting said valves for reducing current flow through said second valve by an amount equal to the current flow through the first valve as occasioned by the action of said pulses on said control element of said first valve, whereby the total current drawn on said source remains constant irrespective of varying load.
